UNITED STATES PATENT OFFICE.

BENNO VOM EIGEN, OF NEWARK, NEW JERSEY, ASSIGNOR TO AUGUST GOERTZ & CO.,
A CORPORATION OF NEW JERSEY.

BAG-FRAME AND HINGE CONNECTION THEREFOR.

1,339,799.

Specification of Letters Patent.

Patented May 11, 1920.

Application filed March 13, 1919. Serial No. 282,254.

To all whom it may concern:

Be it known that I, BENNO VOM EIGEN, a citizen of the United States, residing at Newark, in the county of Essex and State 5 of New Jersey, have invented certain new and useful Improvements in Bag-Frames and Hinge Connections Therefor; and I do hereby declare the following to be a full, clear, and exact description of the invention, such as will enable others skilled in the 10 art to which it appertains to make and use the same, reference being had to the accompanying drawings, and to characters of reference marked thereon, which form a part 15 of this specification.

This invention relates, generally, to improvements in bag-frames; and, the present invention has reference, more particularly, to a novel hinge-connection for the frame-sections thereof, with a view of providing the usual bag-frame with a spring-hinge connection which will permit the frame-sections to be readily brought into their closed and opened relations, and at the same time 20 will act as a stay to positively retain the frame-sections in their opened relation.

The present invention, therefore, has for its principal object to provide a bag-frame, the frame-sections of which are made with 25 spring-hinge connections for the usual purpose of pivotally connecting the frame-sections, and at the same time will provide a connection which acts as a stay to maintain the frame-sections in an open relation and to 30 prevent accidental closing of the mouth of the bag, while at the same time providing for the fullest access to the interior of the bag.

Other objects of this invention not at this 35 time more particularly enumerated will be clearly understood from the following detailed description hereinafter more fully set forth.

With the various objects of the present 40 invention in view, the said invention consists, primarily, in the novel bag-frame and spring-hinge connection therefor hereinafter more fully set forth; and, the invention consists, furthermore, in the novel arrangements and combinations of the various 45 devices and parts, as well as in the details of the construction of the said parts, all of which will be hereinafter more fully set forth, and then finally embodied in the

clauses of the claim which are appended to 55 and which form an essential part of the said specification.

The invention is clearly illustrated in the accompanying drawings, in which:—

Figure 1 is a side elevation of a bag-frame made according to and embodying the principles of the present invention, the hinged or pivotally connected frame-sections being shown in their closed relation; Fig. 2 is an end elevation of one of the 60 hinged portions of the frame-sections; and Fig. 3 is a similar view of the same, looking in the direction of the arrows 3—3 in said Fig. 1, said last two-mentioned views being 65 made on an enlarged scale. 70

Fig. 4 is a vertical sectional representation taken on line 4—4 in said Fig. 3, said view being made on a larger scale; Fig. 5 is a side elevation of the parts represented in said Fig. 3, also on a larger scale, certain 75 parts of the hinge-connection being represented in section; and Fig. 6 is a vertical sectional representation of the same, said section being taken on line 6—6 in said Fig. 4. 80

Fig. 7 is a vertical sectional representation, similar to the section represented in Fig. 4, but showing the two frame-section portions turned at a right angle.

Fig. 8 is a horizontal section, taken on 85 line 8—8 in said Fig. 4; and Fig. 9 is a similar section, taken on line 9—9 in said Fig. 4.

Similar characters of reference are employed in the said above described views, to 90 indicate corresponding parts.

Referring now to the several figures of the drawings, the reference-characters 1 and 2 indicate the two frame-sections of a bag-frame, the said sections being respectively 95 made with the end or pivot-members 3 and 4. As shown in the several figures of the drawings, the lower end-portion 5 of each pivot-member 3 is made with an inwardly extending chambered portion, as 6, preferably pressed by means of a suitable die, directly out of the metal of which the said pivot-member of the frame-section is made, the closed face-portion 7 of the said chambered member 6, being formed with an outwardly projecting rib or projection, as 8, which extends diagonally across said face-portion 7 and is provided with a centrally 100 105

disposed hole or perforation 9. In cross-section, the said rib or projection 8 is convexly formed, as will be clearly evident from an inspection of Figs. 3, 6, 8 and 9 of the drawings.

Suitably secured to the lower end-portion 10 of each pivot-member 4, by means of rivet lugs, as 12, see Fig. 3, or any other suitable fastening means, is a plate 11, said plate being provided at its free end with a laterally extending pivot-member, as 13. This pivot-member 13 is also provided with a rib or projection, as 14, which extends diagonally across said member, said rib or projection 14, in cross-section, being also convexly formed, and its concave surface-portion 15, when the two frame-sections 1 and 2 are in their closed, or in their opened relation, registers with the convex surface-portion of the rib or projection 8, substantially as shown more particularly in Figs. 8 and 9 of the drawings. Likewise, the said rib or projection 14 is made with a perforation or hole 16 in registration with the perforation or hole 9 in the rib or projection 8, and secured in said perforation or hole 16, substantially in the manner illustrated in Fig. 4 of the drawings, is the reduced shank-portion 18 of a pintle or pivot-pin 17. The main shank-portion of each pintle or pivot-pin 17 extends through and is rotatably disposed in the perforation or hole 9 of the projection or rib 8, with its main portion extending through the interior of the chambered portion 6 and from the open part 19 thereof, as shown in Figs. 4, 7 and 9. Upon the projecting end, the main shank-portion of each pintle or pivot-pin 17 has a head or enlargement, as 20, and encircling each main shank-portion, and disposed between the said head or enlargement 20 and the inner wall of the face-portion 7 is a helical spring 21, the purpose of which is to bring the two registering ribs or projections 8 and 14 of each pair of pivot-members 3 and 4 into perfect registration and retaining or holding engagement when the two frame-sections 1 and 2 are in their closed or in their opened relation, and still permit of the rotatable movements of said frame-sections with relation to each other, during the opening or closing operations of the frame-sections, as will be clearly evident.

The openings 19 in the end-portions 5 of the pivot-members 3 are closed by means of suitably formed chambered and ornamental caps, as 21', which are suitably secured in position upon the outer faces of said end-portions, preferably by means of holding or clamping lugs 22 and 23, each lug 22 projecting into and through a perforation or slot 24 and each lug 23 embracing the lower marginal edge-portion 25 of the end-portion 5, and said lugs being securely clamped against

the inner faces of the respective end-portions 5, as more clearly illustrated in Figs. 3, 4, 6 and 7 of the drawings.

Of course it will be clearly understood that any other means may be employed for securing these ornamental caps in position. Having in the foregoing described the general construction of the bag-frame and the spring-hinge connections for the respective frame-sections therefor, it is thought that any further description of the operations of said connections is deemed unnecessary, as such operations will be clearly understood from an inspection of the several figures of the drawings.

I am fully aware, that changes may be made in the general arrangements and combinations of the various devices and parts, as well as in the details of the construction of the said parts, without departing from the scope of the present invention as set forth in the foregoing specification, and as defined in the clauses of the claims which are appended thereto. Hence, I do not limit my present invention to the exact arrangements and combinations of the said devices and parts as described in the said specification, nor do I confine myself to the exact details of the construction of the said parts, as illustrated in the accompanying drawings.

I claim:—

1. In a bag-frame comprising a pair of frame-sections, said frame-sections being formed with end or pivot-members, one of said members having pressed out therefrom an inwardly extending chambered portion, provided with a diagonally extending and perforated retaining rib, a hinge-plate secured to the other of said pivot-members, said plate having a pivot-member provided with a diagonally extending and perforated retaining rib, adapted for separable registration with said first-mentioned retaining rib, a pivot-pin secured in the perforation of said second-mentioned rib, the main shank-portion of said pivot-pin extending into said chambered portion, said pivot-pin being provided with a head, and a spring encircling said pivot-pin between said head and the inner wall of said chambered portion.

2. In a bag-frame comprising a pair of frame-sections, said frame-sections being formed with end or pivot-members, one of said members having pressed out therefrom an inwardly extending chambered portion, provided with a diagonally extending and perforated retaining rib, a hinge-plate secured to the other of said pivot-members, said plate having a pivot-member provided with a diagonally extending and perforated retaining rib, adapted for separable registration with said first-mentioned retaining rib, a pivot-pin secured in the perforation

of said second-mentioned rib, the main shank-portion of said pivot-pin extending into said chambered portion, said pivot-pin being provided with a head, a spring encircling said pivot-pin between said head and the inner wall of said chambered portion, and a cap mounted over said chambered portion.

3. In a bag-frame comprising a pair of frame-sections, said frame-sections being formed with end or pivot-members, one of said members having pressed out therefrom an inwardly extending chambered portion, a hinge-plate secured to the other of said pivot-members, said plate having a pivot-member oppositely disposed to said chambered portion, retaining means connected with said chambered portion and with the pivot-member of said hinge-plate, said retaining means being in separable registration, and a pivot-pin connecting said chambered portion with the pivot-member of said hinge-plate.

4. In a bag-frame comprising a pair of frame-sections, said frame-sections being formed with end or pivot-members, one of said members having pressed out therefrom an inwardly extending chambered portion, a hinge-plate secured to the other of said pivot-members, said plate having a pivot-member oppositely disposed to said chambered portion, retaining means connected with said chambered portion and with the pivot-member of said hinge-plate, said retaining means being in separable registration, a pivot-pin connecting said chambered portion with the pivot-member of said hinge-plate, and a cap mounted over said chambered portion.

40 5. In a bag-frame comprising a pair of

frame-sections, said frame-sections being formed with end or pivot-members, one of said members having pressed out therefrom an inwardly extending chambered portion, a hinge-plate secured to the other of said pivot-members, said plate having a pivot-member oppositely disposed to said chambered portion, retaining means connected with said chambered portion and with the pivot-member of said hinge-plate, said retaining means being in separable registration, a pivot-pin connecting said chambered portion with the pivot-member of said hinge-plate, and a spring encircling said pivot-pin.

6. In a bag-frame comprising a pair of frame-sections, said frame-sections being formed with end or pivot-members, one of said members having pressed out therefrom an inwardly extending chambered portion, a hinge-plate secured to the other of said pivot-members, said plate having a pivot-member oppositely disposed to said chambered portion, retaining means connected with said chambered portion and with the pivot-member of said hinge-plate, said retaining means being in separable registration, a pivot-pin connecting said chambered portion with the pivot-member of said hinge-plate, a spring encircling said pivot-pin, and a cap mounted over said chambered portion.

In testimony that I claim the invention set forth above I have hereunto set my hand this 11th day of March, 1919.

BENNO VOM EIGEN.
